DESIGN.

H. C. ADAM.

LIGHTING FIXTURE.

APPLICATION FILED JULY 19, 1917.

51,294.

Patented Sept. 25, 1917.

Inventor,
Harry C. Adam

UNITED STATES PATENT OFFICE.

HARRY C. ADAM, OF ST. LOUIS, MISSOURI.

DESIGN FOR A LIGHTING-FIXTURE.

51,294.

Specification for Design. Patented Sept. 25, 1917.

Application filed July 19, 1917. Serial No. 181,656. Term of patent 14 years.

To all whom it may concern:

Be it known that I, HARRY C. ADAM, a citizen of the United States, residing at St. Louis, Missouri, have invented a certain new, original, and ornamental Design for a Lighting-Fixture, of which the following is a specification, reference being had to the accompanying drawing, forming part thereof.

The drawing is a side elevational view of

my new ornamental design for a lighting fixture.

I claim:

The ornamental design for a lighting fixture, as shown.

HARRY C. ADAM.

Witnesses:

R. M. TREXLER,
G. W. JOHNSON.
